UNITED STATES PATENT OFFICE.

WILSON E. JURY, OF LANARK, ILLINOIS.

DESIGN FOR A GAME-BOARD.

SPECIFICATION forming part of Design No. 34,045, dated February 5, 1901.

Application filed January 9, 1901. Serial No. 42,699. Term of patent 14 years.

To all whom it may concern:

Be it known that I, WILSON E. JURY, a citizen of the United States, residing at Lanark, in the county of Carroll and State of Illinois, have invented and produced a new and original Design for a Game-Board; and I do hereby declare the following to be a full, clear, and exact description of the same, reference being had to the accompanying drawing, forming a part thereof.

The figure is a plan view of a game-board, showing my new design.

As shown in the drawing, the leading features of my design consist of a picture of the Capitol of the United States *a*, centrally disposed, being inclosed in an octagonal figure having four of its sides shorter than the other four. About this central figure is another figure of similar outline, and from each of its shorter sides extends a series of rectangular figures *b*, forming partial diagonals of a large square about the central figures, and each of the figures in the series *b* being marked with a star, the space between the outer ends of

each pair of said rectangular figures *b* being divided into an equal odd number of oblong figures *c*, the end figures and also the middle figure in each case being distinguished from the others by a series of three figures *d*, substantially diamond-shaped. These said end figures are so arranged as to unite at right angles with each other and at their junction join the outer figure of the series *b*. The space within the said right angle is left plain, thus forming a square at each corner of the board.

Having thus described my invention, what I claim as new, and desire to secure by Letters Patent, is—

The design for a game-board, as herein shown and described.

In testimony whereof I affix my signature in presence of two witnesses.

WILSON E. JURY.
